ATTORNEY

UNITED STATES PATENT OFFICE.

JOHN R. TOWNSEND, OF SOUTH BEND, INDIANA, ASSIGNOR TO GEORGE CUTTER COMPANY, A CORPORATION OF INDIANA.

DESIGN FOR LIGHT-INCLOSING BODY.

Application filed April 1, 1922. Serial No. 1,491. Term of patent 14 years.

To all whom it may concern:

Be it known that I, JOHN R. TOWNSEND, a citizen of the United States, residing at South Bend, in the county of St. Joseph and State of Indiana, have invented a new, original, and ornamental Design for Light-Inclosing Bodies, of which the following is a specification, reference being had to the accompanying drawing, constituting a part thereof.

Figure 1 is a view—one half in side elevation and one half in section—of an elec-

tric-light "globe" showing my new surface design.

Fig. 2 is a detail view—on an enlarged scale—of a small portion of the device shown in Fig. 1.

I claim:

The ornamental design for a light-inclosing body, as shown.

In testimony whereof, I have hereunto subscribed my name this 24th day of March, 1922.

JOHN R. TOWNSEND.
